CLAIM

I claim the ornamental design for a magnet cabinet light assembly, as shown.

DESCRIPTION

FIG. 1 is a perspective view of the magnet cabinet light assembly, shown with a symbolic break in its length, for ease of disclosure.

FIG. 2 is the front view of the magnet cabinet light assembly.

FIG. 3 is a back view of the thereof.

FIG. 4 is a side view of the thereof.

FIG. 5 is the other side view of the thereof.

FIG. 6 is a top view of the thereof.

FIG. 7 is bottom view of the thereof.

FIG. 8 is a perspective view of the magnet cabinet light assembly thereof, shown in an alternate configuration of use within an environmental cabinet; and,

FIG. 9 is a perspective view of the magnet cabinet light assembly thereof, shown in a second alternate configuration of use within an environmental cabinet.

The evenly spaced broken lines shown in FIGS. 8 and 9 illustrate environmental structure. The dash-dot broken lines shown in FIGS. 8 and 9 illustrate the bounds of the environmental structure; all broken lines form no part of the claimed design. The magnet cabinet light assembly is shown with a symbolic break in its length. The appearance of any portion of the article between the break lines forms no part of the claimed design.
